(57) **CLAIM**

The ornamental design for cap light with cluster LEDs, as shown and described.

DESCRIPTION

FIG. 1 is a perspective view of a cap light of the invention;
FIG. 2 is a front elevational view of the invention;
FIG. 3 is a rear elevational view of the invention;
FIG. 4 is a left-side elevational view of the invention, the right-side elevational view being a mirror image thereof;
FIG. 5 is a top plan view of the invention; and,
FIG. 6 is a bottom plan view of the invention.
